SELECTABLE INDEX

John F. Thull, Minneapolis, Minn., assignor to
Brown & Bigelow, St. Paul, Minn.

Application January 2, 1947, Serial No. 719,879

7 Claims. (Cl. 40—104)

1

My invention relates to an improvement in a hinged sheet index particularly adaptable for names and telephone numbers or any other data to which frequent reference is made.

It is an object of my invention to provide an index which is extremely simple to operate having alphabetical data sheets with alphabetical tabs thereon whereby a selection of a sheet may be made by depressing a selected tab with the finger.

In old forms of indexes similar to my invention the rear portion of the body of the index moves upwardly or rocks on a base as the selection is made. This movement is undesirable as it results in a less efficient and rough operating index. In addition, many old forms of indexes require two distinct operations to make a selection of an alphabetical sheet.

It is a primary feature of my invention to provide an index whereby when a selected alphabetical tab is depressed for selection of an indexed sheet, the index unit, composed principally of tabs and sheets, moves and operates simply and smoothly within the body of the index by means of my new hinge and resiliently mounted roller combination. As a result, the body of my unit remains stationary.

As a further primary feature of my invention I provide an index which has a removable index unit composed primarily of alphabetized sheets, tabs, and selecting and retaining mechanism, which unit may be easily removed from the body of the index either for replacement or repair.

It is a further feature of my invention to provide an index whereby a selection or rejection of alphabetized sheets may be made in a simple single operation by slight pressure or release of pressure on an alphabetical tab provided.

An additional object is to provide a body or casing which encloses the index unit including means for separating the indexed sheets consisting of a pulley belt attached to the underside of the lowermost sheet and the topside of the uppermost sheet and positioned around a portion of a roller suitably located to allow positive and smooth separation of the sheets.

I further provide an index whereby the alphabetical sheets are not exposed when the device is not in operation.

The details and features will be more clearly and fully hereinafter set forth together with other objects of my invention.

In the drawings forming a part of this specification:

2

Figure 1 is a perspective view of my index.

Figure 2 is a sectional view on the line 2—2 of Figure 1.

Figure 3 is a sectional view on the line 3—3 of Figure 2.

Figure 4 is a sectional view on the line 4—4 of Figure 2.

Figure 5 is an enlarged detail of a portion of my index similar to one end of the section shown in Figure 2.

Figure 6 is a sectional view on the line 5—5 of Figure 3 in the direction of the arrows.

Figure 7 is a perspective view of the index unit removed from the supporting base.

Figure 8 is a plan view of the bottom of my device.

Figure 9 is a section showing some of the indexed leaves elevated.

Figure 10 is a perspective view of the index opened to a place of reference.

As shown in the drawings, I provide an index base A which is adapted to receive index unit B for operation. The index body A may be formed of metal or plastic or any suitable material. As a part of unit B I provide a flat plate 10 provided with a cross bar 11 extending across the full width of the underside of plate 10 adapted to be positioned on fulcrum 12. Fulcrum 12 is formed inside the body A upon the bottom 12' of the index base A and extends transversely across the width of bottom 12'.

The forward portion of plate 10 is an elongated lip 13 positioned to contact the underside of portion 14 of the body A when the index is not depressed. On each end of lip 13 is an ear 15 which is bent into the dotted line position shown in Figure 7 after the insertion of unit B into the body A.

Ear 15 is bent so that it will fit into recess 15' thereby preventing plate 10 from slipping rearwardly. The groove 16 also holds the unit B from slipping longitudinally. Plate 10 is provided with longitudinal side portions 17 in which are constructed grooves 18 adapted to be positioned on fulcrum 12, the bottom of the groove 16 acting as a fulcrum point together with cross bar 11.

The angle member 18 is formed as a part of plate 10 not to exceed in length the width of plate 10. The lower edge of member 18 rests on the bottom 12' of the base A coincidentally with the lip 13 engaging under portion 14 when the device is not depressed, maintaining the plate 10 in a level position.

A bottom sheet 19 whose area is approximately that of the top of plate 10 is securely fastened to the top of plate 10. Portion 20 of sheet 19 is used as a tab adapted to receive letters of the alphabet to indicate data thereon, as illustrated in Figures 1 and 10. Portion 20 is the only part of sheet 19 which is exposed when the device is not in use. When tab 20 is depressed, the entire sheet 19 is exposed as hereinafter set forth.

Under the inner end of sheet 19 adjacent angle member 18 is secured the lower end 21 of puller belt 22. Puller belt 22 may be of any width, but the preferred width is the width of plate 10. Belt 22 is positioned around a portion of roller 23, and the upper end is secured between the top cover 24 and inner end of sheet 25. Roller 23 rotates on the shaft ends 26 of the shaft 43.

I provide two inner walls 27 positioned in the rear portion of index body A constructed with openings 28. Springs 29 are provided on either end of roller 23 and the openings 28 are adapted to receive the ears 30 of springs 29. The springs 29 are removably positioned and secured with ears 30 against the forward portion of opening 28 and ends 31 positioned under shaft ends 26. The tension of springs 29 holds shaft ends 26 against shoulder points 32 located in openings 28 of walls 27 allowing roller 23 to rotate against shoulder points 32 when the unit is not depressed to any extent.

When the index is not depressed for use, the shaft ends 26 of roller 23 are positioned close to shoulders 32 under the spring tension of springs 29. As a tab is depressed and the inner end of plate 10 moves upwardly and the sheets are opened out flat so that they may be written upon, the shaft ends 26 move on the upper edge of openings 28 toward shoulders 32'. When the sheets are completely separated to the fullest extent, the shaft ends 26 are positioned adjacent to shoulders 32'. The movability of roller 23 is necessary for smooth operation of the unit B and gives a taut puller belt 22 at all times. This movement of the roller 23 and belt 22 is of primary importance as it permits the separation of the sheets selectively with the smallest possible amount of movement of the fulcrumed plate 10 at the front and giving a relatively greater movement of the rear of the fulcrumed plate which gives a strong pull on the belt 22 to raise the sheets. The result of the foregoing provides an index whereby the base A remains entirely stationary and without movement. The unit index operates within the base and normally rests within a pocket formed within the top of the base.

A multiple expansive hinge or binding 33 is made up of a series of folds 42 extending across the width of the metal plate 10 adapted to receive the innermost ends of sheets 19, 34, 35, 36, 37, 38 and 25, in the folds thereof. Each sheet is glued into the folds 42 of the hinge 33 on the top marginal inner end of each sheet. This permits a limited rearward spacing of the sheets when the series of sheets is hingedly opened. At their front edge each sheet is cut away in increasing widths as shown in Figures 1 and 7 to expose a portion of the sheet below, which exposed portion is used as a tab and provided with letters of the alphabet to indicate data thereon. The tabs are alphabetized as illustrated in Figures 1 and 10 and are rounded to facilitate separation of the sheets. The sheets are cut from relatively stiff material to facilitate separation.

The hinge 33 may be made of fabric or any suitable material and need not be a continuous piece. The lower end 39 of hinge 33 is secured to plate 10 by being fastened on the top end 21 of puller belt 22 which is fastened to plate 10 as hereinbefore set forth. The upper end of hinge 33 is secured between the upper end 40 of puller belt 22 and end of sheet 25.

Portion 41 of base A terminates at a point whereby a sheet or sheets and top cover 24 are limited in movement beyond a substantially vertical position.

A varying number of sheets may be employed in my device. On a front portion of each sheet 15 is an exposed tab similar to tab 20 upon which letters of the alphabet are printed to indicate alphabetized data on the particular sheet.

My device is operated by depressing a selected tab. As a tab is pressed downward the forward portion of the plate 10 is adapted to move downward, and simultaneously the rear portion of plate 10 moves upwardly, bar 11 acting on fulcrum 12. The rear end of plate 10 pushes upward on the overlying sheets as a tab is depressed. 20 As the rear portion of plate 10 moves upwardly the puller belt 22 is pulled in the direction of the arrows in Figure 2 against roller 23 thereby drawing into a substantially vertical position all sheets above the sheet selected, as illustrated 25 in Figure 9. The separated sheets are returned to their former positions by releasing pressure on the tab. When the selected sheets are elevated, as illustrated in Figure 9, the hinge 33 assumes the position shown therein. The underside of a raised sheet provides a space for conforming to alphabetical data on the tab depressed such as A, B, C, etc., as illustrated in Figure 10. The information on the underside of a sheet is viewed with the sheet in substantially a vertical position.

It will be apparent that my removable index unit B is composed of plate 10, side member 17, cross bar 11, lip 13, ears 15, angle member 18, a series of sheets with tabs secured to the folds 42 of the hinge 33, a puller belt 22, roller 23, shaft 43, shaft ends 26, and cover 24. It will thus be seen that the index unit B when properly positioned and secured in body A will operate within the body so to speak. The body does not move. 50 In addition, by removing the springs 29 and restoring the ears 15 to the solid line indicated in Figure 7 the index unit B may be removed for adjustment, repair, or replacement.

The top surface of a sheet may be inscribed 55 after it is in a selected position. The underside of a sheet is inscribed by selecting it as hereinbefore set forth and lifting its inner end slightly from the base so that the sheet opens out flat to aid in writing upon it. Also, the 60 sheets may be more easily inscribed by removing the index unit as described whereupon the sheets can be laid out flat so that they can be easily written upon.

I claim:

1. A hinged index comprising a base, a fulcrum positioned transversely on the inner surface of the bottom of said base, a plate adapted to be positioned on said fulcrum, means to limit the movement of said plate on said fulcrum, a series of indexed sheets positioned one upon the other on said plate, an exposed portion on the front portion of each of said sheets forming tabs, a cover for said sheets, a hinge consisting of a series of folds fastened to the rear end of said 70 plate and to said cover for said sheets, the inner 75 plate and to said cover for said sheets, the inner

ends of said sheets fastened into said folds of said hinge, a puller belt fastened to the inner end of said plate and the inner end of said cover, an idle roller over which said belt is adapted to extend, whereby when a tab of one of said sheets is depressed, said sheets are hingedly divided exposing the selected sheets.

2. A hinged sheet index comprising a removable unit of stacked sheets including a multiple hinge to which said sheets are attached at their inner edge, a front portion of each sheet cut away in successively increasing widths to provide tabs thereon, a cover sheet attached to the uppermost of said sheets and the upper end of said hinge, a puller belt attached to said cover and the bottommost of said sheets, a base for supporting said unit, said bottommost sheet fastened to a plate fulcrumed within said base, a roller around which said belt extends, means for removably positioning said unit in said base, whereby when said roller is removed, said unit may be removed from said base.

3. A hinged index including a series of sheets positioned one upon the other, a base, fulcrumed means for supporting said sheets in said base, a multiple hinge adapted to receive the inner ends of said sheets, said sheets indexed on an exposed portion of each of said sheets, a puller belt, one end of said puller belt attached to the inner end of the uppermost sheet, the opposite end of said puller belt attached to the inner end of the lowermost sheet of said series of sheets, a roller, said puller belt positioned around a portion of said roller, shaft ends protruding from the ends of said roller, inner walls positioned in the rear portion of said base, openings in said inner walls adapted to receive said shaft ends, springs adapted to position said shaft ends in said openings in said wall whereby when said fulcrumed means is operated said sheets are separated.

4. A hinged sheet index including a base, a fulcrum secured to the inside of the bottom of said base, said fulcrum being positioned closer to the forward portion of said base than the rear thereof, a plate adapted to rock on said fulcrum, a series of sheets positioned as a unit one upon the other on said plate, a multiple folding hinge connecting the inner ends of said sheets, a cover for said sheets, a puller belt, one end of said puller belt fastened to said cover and the other end of said puller belt to said plate, a roller, said

puller belt extending around said roller, shaft ends protruding from each end of said roller, inner walls positioned in the rear portion of said base, openings in said walls adapted to receive and position said shaft ends, spring means adapted to permit the axis of said roller to change position during the selective operation of said sheets to expose the selected sheets at will.

5. A hinged sheet index comprising a base, a series of sheets positioned within said base, a puller belt fastened to the uppermost of said sheets and the lowermost of said sheets, a roller resiliently positioned in said base around which said puller belt is extended, a plate fulcrumed within said base, said sheets secured to said plate, tabs provided on the free ends of said sheets, whereby when one of said tabs is depressed the sheets above the tab are elevated.

6. A base, a plate fulcrumed within said base, a series of hinged sheets secured to the top of said plate, a hinge secured to the inner end of each of said top sheets, a puller belt fastened to the inner end of the top and bottommost sheet, a roller, resilient means for positioning said roller to hold the same taut against said puller belt, a portion of each of said sheets exposed to form a tab therefor, whereby when one of said tabs is depressed the inner end of said plate elevates pulling said puller with it to separate said sheets, said base remaining stationary.

7. A hinged sheet index including a stack of sheets, said sheets connected at their inner end by an expansive hinge, the bottom of said sheets secured to a plate, said plate fulcrumed within a base, means for limiting the movement of said plate, a puller belt fastened to the inner end of said plate and to the inner end of the top of said sheets, a roller resiliently positioned within the rear of said base, said puller belt extended around said roller, means for raising said inner end of said plate to draw said puller belt around said roller thereby pulling said sheets into a substantially vertical position.
